UNITED STATES PATENT OFFICE.

LEO F. DENEVAN, OF BOVILL, IDAHO.

PRIMING CUP.

Application filed May 17, 1921. Serial No. 470,467.

To all whom it may concern:

Be it known that I, LEO F. DENEVAN, a citizen of the United States, residing at Bovill, in Latah County, State of Idaho, have 5 invented certain new and useful Improvements in Priming Cups, of which the following is a specification.

My present invention relates to an improved priming cup for use with an internal combustion engine, and designed especially as a receptacle or container for pellets or balls which latter are to be used as carbon removers in the cylinder, while the engine is in operation. The balls are 10 to be introduced into the engine cylinder and tossed about therein, by the action of the moving piston for contacting with the walls of the cylinder and the piston head for the removal of accumulated carbon.

20 The primary object of the invention is the provision of a priming cup, which in addition to performing its customary function of supplying the priming charge to the cylinder, is adapted as a receptacle or container for the balls or carbon removers and from which the latter may be dispensed and introduced into the cylinder as required.

With the above object in view the invention consists in certain novel combinations 30 and arrangements of parts as will be hereinafter more specifically pointed out and claimed.

In the accompanying drawings I have illustrated one complete example of the 35 physical embodiment of my invention wherein the parts are combined and arranged according to the best mode I have thus far devised for the practical application of the principles of my invention.

40 Figure 1 is a view in side elevation of the priming cup embodying my invention.

Figure 2 is a vertical central sectional view of the device of Figure 1.

Figure 3 is a top plan view of the device.

45 Figure 4 is a view in side elevation of the receptacle or shell removed from the cup.

In the preferred form of the invention as illustrated in the drawings I utilize the well known form of open top cup 1 usually employed for priming the engine, and located above the engine cylinder, the body casting 2 having a threaded nipple 3 which is screwed into the cylinder head to provide means for introducing a priming charge of 55 gasoline or gas from the cup. The plug valve 4 is fashioned with the usual trans-

verse port 5 to register with the passage or bore 1^a through the body and nipple, and the valve is manipulated by its handle 6 for opening or closing the passage, either 60 for introduction of the priming charge or to permit several of the balls B to pass to the engine cylinder to act therein as carbon removers.

The balls or spheres B are contained in 65 a perforated shell or receptacle 7, which conforms in shape to the interior of the cup and is designed to be received therein as in Figure 2. At its lower end the receptacle is provided with a nozzle or spout 8 which 70 fits into the upper end of the passage 1^a of the casting to seat the receptacle in proper position, and to insure flow of gasoline, when priming the engine, through the casting to the cylinder. And the perforated receptacle, 75 it will be apparent insures freedom of movement of the liquid within the cup without interfering with its passage to the cylinder. As seen in Figure 2 at 7^a the wall of the receptacle may be inset with relation to 80 the cup to provide space for the gasoline, if desired.

At its upper edge, the open receptacle is fashioned with an annular, outwardly projecting flange 9 to seat upon the edge of the 85 cup, and a cover 10, with an overhanging sleeve 11, is provided for the cup and receptacle. At 12 the overhanging sleeve is provided with one or more bayonet slots 12 extending circumferentially around the 90 cover for the required distance, to co-act with complementary pins 13 projecting outwardly from the outer face of the cup, for securing the cover in locked position on the cup and receptacle. By utilization of this 95 slot and pin connection it will be apparent that the cover may be applied to or removed from the cup as required.

For the introduction of gasoline and the 100 pellets or balls B to the cup, a slide lid 14 is centrally pivoted at 15 on the dome shaped cover to act as a closure for the opening 15^a in the dome shaped cover, through which opening the balls or gasoline may be introduced.

When priming the cylinder, the valve is 105 turned to open position as in Figure 2, and gasoline is permitted to flow through the perforated receptacle to the nozzle 8, a large portion thereof passing through the open 110 pocket or space formed between the cup and the inset portion 7^a of the receptacle to

make direct communication with the interior of the nozzle and thence with the open passage 1^a in the casting body. Because of the interstices between adjoining balls in the receptacle a considerable quantity of gasoline is contained in the receptacle below the surface of the mass of balls, and of course the receptacle above the top surface of the mass of balls also contains gasoline for use in priming. Only a sufficient number of balls will be introduced to the receptacle for use as carbon removers as will also permit the introduction of the required quantity of gasoline to the cup for priming purposes. Or if desired, the balls may be introduced to the receptacle, or the receptacle with balls therein placed in the cup only at the time the balls are to be used for removing the carbon.

In any event, a predetermined number of balls are introduced to the cylinder and the movement of these balls, say three in number, is controlled by the port or slot 16 in the bottom of the receptacle. By turning the receptacle within the cup, through the medium of the sleeve 11, the slot or port 16 is brought into alinement or register with a pocket or groove 17 in the bottom of the cup, and when this movement is accomplished, three balls are permitted to pass through the slot into the pocket, as indicated in Figure 2.

Now by turning the receptacle within the cup, a vertically disposed slot 18 in the nozzle 8 is brought into alinement with the groove or pocket 17 permitting the three balls in the pocket to roll into the nozzle, thence into the passage 1^a and into the cylinder of the engine above the piston. The perforated bottom of the receptacle has closed egress of balls from the receptacle to the pocket, thus permitting only the predetermined number of three balls to move to the cylinder. With the engine in operation the reciprocating movement of the piston will cause the three balls to be tossed about in the cylinder and the balls contact

with or strike the inner walls of the cylinder and the head of the piston to knock or remove the carbon therefrom.

From the above description taken in connection with my drawings it will be apparent that the cup may readily be adapted for its usual functions, by opening the valve to admit a priming charge, and by manipulating the receptacle as described, with the valve in open position, the required number of pellets or balls are passed to the cylinder for cleaning the interior thereof. After the priming charge has been admitted, and after the pellets have been admitted, the valve is of course closed.

Having thus fully described my invention, what I claim as new and desire to secure by Letters Patent is—

1. The combination with a priming cup, of a removable attachment comprising a receptacle rotatable therein and having a slotted bottom, co-acting means on the cup and receptacle for retaining and guiding the latter, and said cup having a pocket formed in its bottom to receive a predetermined number of pellets through said slotted bottom.

2. The combination with a priming cup, its valve casing and valve, of a rotatable receptacle within the cup having a slotted bottom, said cup having a bottom pocket adapted to register with said slotted bottom, a nozzle at the bottom of the receptacle, said nozzle having a slot therein to register with said pocket, for the purpose described.

3. The combination with a priming cup, a valve casing and valve, said cup having an open pocket fitting into its bottom, of a perforated receptacle having a slotted nozzle in the valve casing, said receptacle having a bottom slot, whereby the receptacle may be rotated to alternately engage said nozzle slots with said pocket for the purpose described.

In testimony whereof I affix my signature.

LEO F. DENEVAN.
